UNITED STATES PATENT OFFICE.

JOSEPH BOYD, OF CLONBUR, IRELAND.

PUTTEE AND METHOD OF MAKING THE SAME.

1,307,235.

Specification of Letters Patent. Patented June 17, 1919.

Application filed April 25, 1919. Serial No. 292,719.

To all whom it may concern:

Be it known that I, JOSEPH BOYD, a subject of the King of Great Britain and Ireland, of Ebor Hall, Clonbur, Co. Galway, Ireland, have invented new and useful Improvements in Puttees and Methods of Making the Same, of which the following is a specification.

This invention relates chiefly to puttees, 10 and particularly to their application as military equipment.

Puttees, as now supplied to the soldiers who are compelled to wear them, have serious defects and cause such bad results, it 15 is of imperative importance that a properly fitting and properly constructed puttee should be supplied to the army.

My invention relates to the production of such a puttee.

20 Puttees are available made from a straight bandage and molded on a former with the aid of steam which are spiral in form and follow the contour of the leg but the shape is obviously not permanent. My invention 25 aims at a spirally woven or knitted puttee with a permanent curve of about $\frac{3}{4}$ inch in 12 inches where needed, and possessing other important improvements.

Before describing my invention and its 30 advantages I may usefully point out the disadvantages of the present puttees as served to the soldiers.

It is a woven or knitted fabric made quite straight and it is impossible to apply it 35 evenly on the calf of the leg, as the circumference of the leg at the upper margin of the puttee convolution is about 3 inches greater than at its lower margin. The unfortunate wearer is condemned to drag the 40 puttee so tight across his leg that he strangles both his muscles and his circulation at the upper margin, while he is unable to bring the lower margin sufficiently close to the leg and it gapes badly. In the vain 45 endeavor to make the puttees spiral by wearing them he suffers torture, distorts the shape of his leg, is unable to march his normal distance and finally fails (no matter how long he wears them) to produce anything but a slight and quite inadequate spiral on his puttee.

This aggravates the varicose veins of the wearer resulting in depression and lowering of his morale. There is no way of fixing the 55 lower end of the puttee to the boot to prevent slipping, and thus make sure of the up-

per end finishing at regulation point, and his time in consequence is wasted removing and re-applying. Finally he cannot do physical drill without removing his put- 60 tees.

These and other disadvantages are overcome by my invention which I shall now describe in detail, with the aid of the accompanying drawings in which Figure 1 shows 65 the inner side of an unfinished left puttee knitted or woven on the curve about $9\frac{1}{2}$ feet long and laid flat.

Fig. 2 (on twice the scale of Fig. 1) shows the knee end of the same puttee and Fig. 3 70 is a similar view of the boot end. Figs. 4, 5 and 6 show the same knee end in successive stages of development, and Fig. 7 its final form, while Fig. 8 illustrates the final 75 appearance of the boot end of the puttee.

The fabric blank of my puttee may be composed of warp and weft threads crossing each other as in ordinary weaving, or made from loops as in knitted or hosiery fabrics but in either case I prefer to use thread or 80 yarn made from wavy elastic wool of the merino type.

A left puttee blank woven on the curve, preparatory to being treated by my process, is shown by A in Fig. 1. Portions *k* and *b* 85 (marked with cross hatch lines) intended for the knee and boot ends respectively are subjected to treatment which will evert, that is to say, reverse the curvature as fully explained hereinafter.

To weave the fabric on the curve, the warp threads are taken not off a warp beam but off spools weighted—a method well known to weavers. They are thus more easily pulled out in the process of weaving and 95 made gradually longer toward the outer or larger curve of the fabric by the conical drum or beam to be presently described.

As regards the conical drum or beam, this 100 is best placed in front of or takes the place of the breast beam in the loom, and is covered with perforated tin or tentered to keep the warp or cloth from slipping as it rolls over it.

The cone is so graduated that if it is required to weave say a puttee 4 inches wide with an inner curve of 1 inch to the foot, then the cone is made of 12 inches in circumference where the inner curve of the fabric passes over it as it is woven, while it is about 110 15 inches in circumference where the outer or larger curve of the fabric passes over it.

After the woven fabric passes over the conical drum or beam thus described it is received and wound on the piece beam or drum which is also conical and similar to the 5 drum just described.

It is evident that in weaving thus the cross threads or wefts radiate from the smaller curve of the fabric and diverge toward the larger curve where they are farther apart.

10 This gradually increases the size of the spaces between the threads at and toward the outer or larger curve and makes the fabric there thinner and looser in texture.

To counteract this I interpose additional 15 cross threads at intervals during the weaving extending only partly into the fabric and in proportion to its width. Should the fabric be wide it might be necessary to interpose a second series of cross threads near the 20 margin and only for a short distance into the fabric. This process is well known to the weaver and can be carried out by the ordinary harnessing of the loom or on the jacquard system.

25 Where puttees are required narrow I can instead of using the above process secure uniformity of texture simply by placing the warp threads gradually nearer to each other toward the outer margin, or gradually increasing their size.

To prevent raveling or slipping of the upper folds of the puttee over the lower ones—which frequently occurs on the march or in action when puttees are smooth as now in 35 use—I weave longitudinal ridges on the fabric by having an occasional warp thread thicker than the others, and diagonal ridges can be produced by twill weaving. Either device makes the folds adhere firmly.

40 As thus woven $9\frac{1}{2}$ feet makes one puttee blank which is approximately semicircular when laid on a flat surface as shown by A in Fig. 1. To reduce the curve at both ends I subject them to soap and water treatment 45 similar to the process of "fulling" which is well known to the trade. A length k of $2\frac{1}{2}$ feet of the knee or upper end and $1\frac{1}{2}$ feet b of the boot or lower end are thus treated and dried rapidly while the inner curves 50 only are tightly stretched on a board. This absorbs the curve as the inner margin is stretched and the fulling contracts the outer margin. Such contraction may be assisted by adding carbonate of soda.

55 This is illustrated in Fig. 2, in which a denotes the edge which is stretched straight or even slightly averted into a convexity by pins such as P P. The unstretched area c contracts under the influence of the soap and water, assisted, if necessary, by carbonate of soda as mentioned.

60 Two or three small plaits $d d$ (Fig. 4) are now put in the upper margin c , which was originally convex.

65 The end of the puttee is then tapered in

the following manner. I fold the upper margin c like a hem (Fig. 5) over the inner side (preferably) of the puttee beginning with a very fine hem at a point α , 2 feet from the end and ending about $1\frac{1}{2}$ inches wide at 70 the end $y z$. While the tension along the line from α to z (Fig. 5) is maintained stretching it about 2 inches longer than the lower margin a the long triangular fold c (Fig. 5) is stitched along its edge by stitches 75 f to the portion on which it lies, while this and the unstretched part a is pushed away or back from the end by the person stitching it so as to keep it in as relaxed a condition as possible causing it to become crimped. 80 About 6 inches of the lower edge at z having been previously tucked in between the folds at the end, the folds are pressed and stitched, as shown by h in Fig. 6. The last two feet of the puttee are in this manner everted as 85 shown. This enables the puttee to fit accurately below the knee without puckering.

Finally the end of the puttee is capped for about three inches of its length with closely woven fabric l (Fig. 7), this fabric 90 being about one inch wide and folded upon itself longitudinally to embrace the end of the puttee. The corners of the fabric l are rounded as at m where the ends are sewn into the puttee at the free end. Its use is to 95 stop raveling of the end and to receive a hook n which secures the end of the puttee when worn and obviates the use of 6 feet of tape. Other advantages of this tapering are 100 esthetic and practical, when the puttee is worn. The hem g (Fig. 7) makes the upper margin of the puttee doubly strong. The tapered part cannot be overtightened on account of its structure while it makes a very neat finish instead of the ugly square finish 105 of the present puttee.

I finish the boot end of the puttee (after straightening it as shown in Fig. 3) in the manner shown in Fig. 8. I fold the lower edge of the boot end outside in 110 for about 12 inches from p to q tapering in width to $1\frac{1}{2}$ inches at the end and I tuck in between the folds the projecting edges. The ordinary puttee is soon worn here by the friction of the boot and this fold protects my puttee. 115

To protect the lower margin still further I stitch a closely woven curved tape r 10" by $1\frac{1}{2}$ " so as to extend 5 inches along the lower folded margin, the remaining 5 inches projecting beyond the end.

120 Into this tape I fix a detachable hook s such as is disclosed in my British Patent 7536 of 1915 to attach the puttee to the boot and keep it from slipping.

125 This hook s can be changed at will by the wearer to any point along the tape to enable the upper end of the puttee to finish at regulation point.

As regards knitted or hosiery fabrics, or 130

warp loom fabrics which have warp threads similar to ordinary weaving, the process of knitting the puttee fabric on the curve is very simple.

5 I need not describe the process of making fabrics from loops—it is too well known to the trade.

Suffice it to say that the loops on the inner curve of the puttee fabric, may by my invention 10 be knitted smaller, becoming gradually longer toward the outer and larger curve.

The size of the loops in hosiery fabrics as is well known is determined by the distance 15 the jacks are allowed to fall. This is regulated by the falling bar which can be raised or lowered by screw-nuts at either end. It is an easy matter therefore to graduate the size of the loops by slanting or lowering the bar at the side where the loops are to be 20 larger.

My process of knitting on the curve applies to both knitting with a single thread, or where warp threads are used.

As thus made my improved puttee has the 25 following advantages in addition to those already mentioned. It looks well and shows the curves of the leg. It fits quite closely yet softly, at the lower margins of the folds without any dragging. Indeed on any part 30 of the leg it can be pinched out nearly an inch resuming its position perfectly owing to its softness and elasticity. It allows full ankle action and muscular action and there is no feeling of constriction at any point. 35 Its length is only 9½ feet materially less than the puttee now in use and it therefore saves valuable time.

I claim:—

1. A method of making puttees consisting 40 of making a flat fabric blank in the form of a curve and then straightening the two ends for a suitable distance for the knee and ankle portions by soap and water treatment, during which the area near the concave edge is 45 permanently stretched and the remaining area near the convex margin allowed to contract.

2. A method of making puttees consisting 50 of making a flat fabric blank in the form of a curve and reversing the curvature at the

two ends, by shaping it while in a plastic state under soap and water treatment.

3. A method of making puttees, consisting of making a flat fabric blank in the form of a curve and reversing the curvature at the 55 two ends by shaping it while in a plastic state under soap and water treatment and plaiting the convex margin.

4. A method of making puttees consisting of making a flat fabric blank in the form of 60 a curve, straightening the two ends in such manner as to form elastic portions therein, putting elastic portions under tension and sewing them while in such condition to portions not under tension in order to evert the 65 latter with respect to their original curvature when the tension is relaxed.

5. A method of making puttees consisting of making a flat fabric blank in the form of a curve and reversing the curvature at the 70 two ends by first straightening the ends for a suitable length corresponding to the knee and ankle portions by soap and water treatment, leaving the outermost area contracted 75 and elastic and the innermost area stretched and relatively inelastic, then inserting plaits in the outer margin, and making a long triangular fold of the latter and stretching and stitching it upon the inner area, so that when it is relaxed the desired eversion is produced. 80

6. A method of making puttees consisting of making a flat fabric blank in the form of a curve and then straightening the two ends for a suitable distance for the knee and ankle 85 portions by soap and water treatment, during which the area near the concave edge is permanently stretched and the remaining area near the convex margin allowed to contract, and tapering the ends by folding the upper and lower margin for a short distance at each end for the knee and ankle portions respectively. 90

In testimony whereof, I have signed my name to this specification in the presence of two subscribing witnesses.

JOSEPH BOYD.
